UNITED STATES PATENT OFFICE.

JOSEPH D. GALLAGHER, OF GLEN RIDGE, NEW JERSEY, AND HARRY JONES, OF SUFFERN, NEW YORK, ASSIGNORS TO AMERICAN BRAKE SHOE & FOUNDRY COMPANY, OF MAHWAH, NEW JERSEY, A CORPORATION OF NEW JERSEY.

BRAKE-SHOE.

1,159,007.

Specification of Letters Patent. Patented Nov. 2, 1915.

Application filed May 4, 1915. Serial No. 25,683.

To all whom it may concern:

Be it known that we, JOSEPH D. GALLAGHER, a citizen of the United States, and a resident of Glen Ridge, county of Essex, 5 and State of New Jersey, and HARRY JONES, a citizen of the United States, and a resident of Suffern, in the county of Rockland and State of New York, have made and invented certain new and useful Improvements in Brake-Shoes, of which the following is a specification.

This invention relates to brake shoes.

An object of the invention is to provide a brake shoe formed of a number of hard 15 and soft sections, so as to combine the requisite frictional properties with long wearing qualities.

In the casting of brake shoes having hard and soft sections, the usual practice has been 20 to make one integral casting of what is known as chilling iron, that is, an iron which, when cast against a chill block, will become hardened and chilled. In brake shoes, as thus formed, it has been extremely 25 difficult, and on a manufacturing scale, practically impossible, to produce a uniform product, that is, brake shoes all of which will have the same amount of chilled and soft metal, the chill oftentimes varying 30 from a quarter of an inch in depth to an inch and a quarter, owing to the conditions under which the shoes are made, and even though the iron was all obtained from the same cupola, and even from the same tap of 35 that cupola. Again, often in obtaining the proper depth of chill, the conditions of pouring might be such that the iron in the sections intended to be soft would be partly chilled, and the frictional effect of the section 40 either materially reduced or lost. Again, in making brake shoes having alternating chilled and unchilled sections in one casting, the process of chilling sets up in the internal structure of the shoe very severe 45 strains and stresses, which again constantly vary, and brake shoes apparently perfectly sound may be, on account of these strains and stresses, very weak in structure and readily go to pieces in service, especially 50 under the conditions of repeated heating and cooling, due to the service it performs. To overcome this lack of uniformity, and weakness in chilled shoes, it has

been the practice to embed in the body of the brake shoe, hard iron or steel dove-tailed inserts, which are held in their place by the cast metal of the shoe body, thereby insuring during the life of these inserts, a uniform distribution of hard and soft sections on the wearing face of the shoe. The 60 objections to this practice are that as it is not practical to make the inserts of the full depth of the shoe, that is, of thickness sufficient to extend from the face to the back of the shoe, the inserts wear out before the 65 shoe is worn out and then the composite wearing face is lost and the face becomes simply the cast iron wearing surface provided by the body metal of the shoe. As the braking pressures required for a composite 70 surface are entirely different from those required for a plain surface of cast iron, the change from one surface to the other, without change in brake pressure, is apt to have a bad effect both on the brake mechanism 75 and the wheel. Another objection to this practice lies in the fact that these inserts, owing to the severe conditions of service, are apt to become loosened and detached from the shoe, changing the character of the 80 wearing face and leaving pockets therein which are apt to result in the scoring of the wheel.

It is among the objects of the present invention to provide a type of brake shoe 85 wherein a substantially uniform brake shoe can be produced, and one that will be free from the weakness of chilled shoes and the wearing surface of which will remain unchanged throughout its life, and with this 90 end in view, two metals are used, one a hard metal, which may be a chilling metal possessing the required properties, and secondly, a soft metal, which possesses the exact characteristics of softness, so that an 95 extremely efficient composite wearing body is obtained, and these metals extend from the face to the back of the shoe.

A further object is to provide a brake shoe formed of a number of separated sections, 100 with a distinct division or spacing between each section, so that although the shoe become heated by contact with a car wheel, it will not straighten out, but will maintain its original contour, each section being allowed 105 to expand independently of the adjacent

ones, and the strains and stresses found in a chilled shoe, and to a considerable extent in the usual insert shoe, will be absent.

A further object is to provide a brake shoe with a reinforcing back, to which are anchored hard and soft sections, and in which is incorporated a reinforcing member in the form of a bundle of expanded metal or wire mesh, the same extending throughout the entire length of the sections, whereby all are anchored and tied together, as well as being securely anchored to the reinforcing back. Each section, in itself, therefore possesses a composite wearing surface made up of the cast metal of the section and the malleable metal of the reinforcing member.

Other objects and advantages will appear as the description proceeds, wherein it is to be noted that changes in the precise embodiment of the invention can be made within the scope of what is claimed, without departing from the spirit thereof.

The preferred embodiment of our invention is disclosed in the accompanying drawings, wherein:—

Figure 1 is a view in plan of the back of a brake shoe embodying the novel features of our invention; Fig. 2 is a plan view of the front or wearing face thereof, with portions broken away to more clearly disclose the various features of construction; Fig. 3 is a view in side elevation, partly in section, of our novel brake shoe; and Fig. 4 is a cross-sectional view taken on the line 4—4 of Fig. 1.

Referring specifically to the several views, a reinforcing back 10 is provided with the integral lug 11, and is formed with the openings 12 extending lengthwise of the back, and both sides of the longitudinal center thereof. The reinforcing back is of the usual and preferred form, and has associated therewith a bundle of expanded metal or wire mesh 13, the same acting as a reinforcing or binding member for the sections of the shoe, and is substantially equal in length to the length of the reinforcing back.

The body or wearing portion of the shoe includes the hard metal end sections 14—14, which are poured or cast around the expanded metal or wire mesh 13, the shoe being preferably placed on end, during such procedure; it being noted, however, that the exact manner in which the shoe is built up forms the subject-matter of a separate application. The hard metal end sections are securely and rigidly anchored to the reinforcing back by the end stops 15, which are formed by the metal which flows up, and around, and embeds, the ends of the reinforcing back therein. After the end sections become sufficiently hardened, the soft metal central section 15^a is cast about the reinforcing member 13, and is accordingly

securely anchored to the hard metal end sections, and is also securely anchored to the reinforcing back by the metal which flows up through the openings 12.

The separate and independent casting of the various sections provides a distinct line, or division, or space, between each section, allowing them to expand independently, so that although the sections become heated during service, the original and proper contour of the shoe will be preserved. The isolation, or slight separation, of each section of the shoe also materially increases the radiating surface thereof, and provides ample opportunity for the dissipation of such heat as is generated therein. The exact number and arrangement of the hard and soft metal sections may be varied, as desired, as is consistent with the requisite frictional and wearing qualities.

What we claim is:—

1. A brake shoe provided with a reinforcing back and having a body anchored thereto, said body being formed of separated sections of hard and soft metals.
2. A brake shoe comprising sections of hard and soft metals, and a reinforcing member of openwork metal embedded in said sections.
3. A brake shoe comprising separated sections of hard and soft metals, and a reinforcing member of openwork metal embedded in said sections.
4. A brake shoe comprising a reinforcing back, separated sections of hard and soft metal anchored thereto, and a reinforcing member of openwork metal embedded within said sections.
5. A brake shoe comprising a reinforcing back, a bundle of openwork metal extending the entire length thereof, and separated sections of hard and soft metal anchored to said back and embedding said openwork metal therein, said sections extending from the face to the back of the shoe.
6. A brake shoe comprising a reinforcing back, a binder extending substantially the entire length thereof, and sections of relatively hard metal anchored to said back and embedding the binder therein, and a section of relatively soft metal anchored to said back and embedding said binder therein.
7. A brake shoe comprising a reinforcing back and a body formed of sections of relatively hard and soft metals cast to said back.
8. A brake shoe comprising a reinforcing back and a body of isolated sections of relatively hard and soft metals cast to said back.
9. A brake shoe comprising a reinforcing back and a body formed of sections of relatively hard and soft metals cast to said back, said sections extending from the face to the back of said shoe.

10. A brake shoe comprising a reinforcing back and a body formed of isolated or separated sections of relatively hard and soft metals cast to said back, said sections extending from the face to the back of said shoe.

11. A brake shoe comprising a reinforcing back, sections of hard metal cast to said back and disposed at the ends thereof, and a section of relatively soft metal cast to said back and disposed between the said end sections.

12. A brake shoe comprising a reinforcing back, and isolated or separated sections of hard and soft metals cast to said back, and a binder extending substantially the entire length of, and embedded within, said sections.

13. A brake shoe comprising a reinforcing back, a bundle of openwork metal extending substantially the entire length thereof, and sections of hard metal anchored to the ends of said back and embedding the ends of said openwork metal, and a section of soft metal between said hard metal ends and separated therefrom.

14. A brake shoe comprising a reinforcing back, a bundle of expanded metal extending substantially the entire length thereof, and sections of hard steel anchored to the ends of said back and embedding the ends of said expanded metal and a section of soft metal between said steel ends, but separated therefrom.

15. A brake shoe comprising a reinforcing back, a bundle of expanded metal extending substantially the entire length thereof, and sections of hard crucible steel anchored to the ends of said back and embedding the ends of said expanded metal, and a section of comparatively soft metal between said crucible steel ends, but separated therefrom.

16. A brake shoe comprising a reinfor-

cing steel back, a bundle of expanded metal of substantially the thickness of the completed shoe extending substantially the entire length of the completed shoe and sections of hard crucible steel anchored to the ends of said back and embedding the ends of said bundle of expanded metal and a section of comparatively soft iron between said crucible steel ends but separated therefrom.

17. A brake shoe comprising a reinforcing back, a bundle of openwork metal extending substantially the entire length thereof, and sections of hard metal anchored to the ends of said back and embedding the ends of said openwork metal and extending from the face to the back of the shoe, and a section of soft metal between said hard metal ends and separated therefrom.

18. A brake shoe comprising a reinforcing back, a binder extending substantially the entire length thereof, sections of metal cast upon said reinforcing back and embedding said binder therein, said sections possessing long wearing qualities, and a section of metal disposed between the aforementioned sections, cast to said back and embedding said binder therein, said section possessing high frictional qualities.
